CLAIM

The ornamental design for a holder for a garden hose nozzle, as shown and described.

DESCRIPTION

FIG. 1 is a perspective view of a holder for a garden hose nozzle showing my new design;

FIG. 2 is an enlarged perspective view thereof;

FIG. 3 is an enlarged right side elevational view thereof;

FIG. 4 is a left side elevational view thereof;

FIG. 5 is an enlarged top plan view thereof; and,

FIG. 6 is an enlarged bottom plan view thereof.

FIGS. 2-4 are shown broken away for convenience of illustration.
